DUPLICATING MACHINE

Alfred Marchev and John W. Hernlund, La Grange, Ill., assignors to Ditto, Incorporated, Chicago, Ill., a corporation of West Virginia

Application October 7, 1933, Serial No. 692,679

5 Claims. (Cl. 242—74)

This invention relates to improvements in duplicating machines and, more especially, to the gelatin band-carrying spindles thereof and the fastening clips adapted for attaching the 5 end of said band to the spindle.

Among the features of our invention is an improved construction permitting easy attachment of the end of the band to the spindle and so made that when the band is unwound from 10 the spindle and the end reached, said band will detach itself from the spindle, thus lessening or eliminating danger of tearing or breaking of the band.

Another feature of our invention is a spindle 15 with improved means for rotatably supporting the same in the machine.

Other features and advantages of our invention will appear more fully as we proceed with our specification.

20 In those forms of devices embodying the features of our invention shown in the accompanying drawings—

Figure 1 is a vertical sectional view through the spindle showing the end of a gelatin band 25 attached; Fig. 2 is a similar view in top plan; Fig. 3 is a view taken as indicated by the line 3 of Fig. 2; Fig. 4 is a view taken as indicated by the line 4 of Fig. 2, on an enlarged scale; Fig. 5 is a view similar to Fig. 4 showing the 30 band detaching itself from the spindle; Fig. 6 is a view similar to Fig. 2 showing a modified form; Fig. 7 is a view taken as indicated by the line 7 of Fig. 6; Fig. 8 is a vertical sectional view through the end of the spindle; Fig. 9 is 35 a view taken as indicated by the line 9 of Fig. 8; Fig. 10 is a view taken as indicated by the line 10 of Fig. 6; and Fig. 11 is a view similar to Fig. 6, showing a modification in the end of the spindle.

40 It is to be understood that the gelatin band, which may be referred to as the band, is of the kind commonly used upon duplicating machines of the hectograph type in which there is employed a long strip or band of material 45 having thereon a gelatin coating. This strip with the coating thereon in its entirety may be referred to as the gelatin band or as the band. The gelatin coating itself ordinarily does not have enough strength to be used alone and, 50 consequently, it must be provided with some sort of backing in the nature of a flexible strip or band of material which has more strength than the gelatin and to which the gelatin will adhere. Consequently, in common practice, only 55 the end of this strip of backing material is

fastened to the spindle by means of a fastening clip attached to it. For convenience, however, the backing material, being a part of the entire gelatin band, may commonly be referred to as the band itself. Therefore, in speaking of a clip attached to the end of the gelatin band or to the end of the band, or in speaking of the attachment of the end of the gelatin band, or the band, to the spindle, it is to be understood that this may refer only to the backing material itself forming a part of the band. In other words, in speaking of the band, or gelatin band, hereinafter, it is to be understood that this may mean only the backing material of the band upon which the gelatin coating is 15 carried.

It is to be understood, also, that the spindles shown herein and the band carried thereby are adapted for use upon hectograph duplicating machines of a conventional type which are now 20 in common use; and that, therefore, it is not necessary to show all the details of such machines in order to disclose this invention.

As shown in the drawings, 20 indicates a spindle, here shown in the form of a cylinder, 25 made of sheet metal having its edges fastened by the longitudinal crimped seam 21.

22 indicates the gelatin band adapted to be carried by the spindle 20 and wound onto and off of the same in the operation of a duplicating 30 machine. In the use of such a machine, it is customary to wind the band back and forth from one spindle to another. In doing this it is necessary to attach one end of the band to the receiving spindle at the commencement of 35 one winding operation. When this receiving spindle is full, the operation of the machine is reversed and the band is wound off of said spindle. During this operation, when the end of the band is reached, it is necessary or desirable that 40 the same detach itself automatically from the spindle in order to prevent breakage or tearing. To this end we have provided an attaching means or fastening clip for the end of the band which can be easily and quickly attached to a 45 spindle and which is self-detaching when the band is unwound from such spindle. It is obvious that one or both ends of the band can be provided with such attaching means and, consequently, we have here shown but one end. 50

The spindle 20 is provided with an elongated flattened face 23 which is here shown as centrally arranged and extending a distance equal to about one-half the length of the entire spindle. This flattened face 23 is provided with 55

a centrally arranged slot 24. For convenience in manufacture, the flattened face 23 is formed adjacent the seam 21, as shown in Fig. 5. As here shown, the face 23 is wide enough to form 5 a chord subtending an arc of about 50° of the circumference of the spindle 20.

The end of the band 22 is provided with a fastening clip or anchor serving as an attachment to the spindle, the clip being described in 10 our co-pending application, Serial No. 692,680 filed October 7, 1933. This fastening clip is made out of a single piece of flat sheet metal and the clip in its entirety is indicated by 30. The clip includes primarily a convexed portion 31 and a 15 tongue 32 adapted to be inserted in the slot 24. Means are provided for attaching said clip to the end of the band 22. The clip shown in Figs. 4 and 5 is made out of one piece of sheet metal and, as there shown, the tongue 32 is of double 20 thickness and attached to one edge of the portion 31 by the portion 33. The two thicknesses of the tongue 32 are indicated by 34 and 35, the latter joining the portion 33. The other thickness 34 is extended inwardly between the portions 25 31 and 33, as indicated by 36. The end of the band 22 is preferably attached to the clip by passing it under the portion 31, thence around the free edge of the portion 36 and thence down into the double tongue 32 between the walls 34 30 and 35. In Fig. 4, the extreme end of the band 22 is indicated by 22a. The tongue 32 is slanted somewhat with respect to the member 31 in the direction that the band extends so that a tangential pull on the band, as shown in Fig. 4, 35 will cause the tongue 32 of the clip to hook in the slot 24. When the band is completely unwound, however, and the pull becomes somewhat more than tangential, as shown in Fig. 5, this pull readily engages the tongue from the slot, thus causing self-detachment of the band from the spindle.

It will be noted that the tongue 32 is substantially straight as distinguished from the usual hook provided for this purpose.

45. In Figs. 6, 7 and 11 we have shown a somewhat different form of fastening clip and spindle construction. As here shown, the band is indicated by 122 and the clip in its entirety is indicated by 130. Here, again, the clip is formed of a 50 single piece of sheet metal and includes the convex portion 131 and slanting tongue 132. The outer edge of the tongue is also joined to one edge of the portion 131 by the portion 133. Here the tongue also is shown double, but there 55 is no portion extended between the portions 131 and 133. The end of the band 122 is indicated by 122a and the same is attached to the clip by clamping the same between the portions 131 and 133 of the clip.

60. In the form of Figs. 6 and 7 the spindle is indicated by 120 and the same is provided with a flattened face 123, but instead of having an open slot such as 24, the face 123 is here provided with a depression or trough 124, the walls 65 of which 124a diverge inwardly. Attachment of the band is effected by inserting the tongue 132 of the clip in the trough and this tongue being slanted, engages one of the walls 124a of the trough. Detachment is effected in the same 70 manner as indicated in Fig. 5. That is, as soon as the pull on the band is somewhat outwardly or away from the spindle, this serves to pull the tongue 132 out of the trough and disengage the clip from the spindle.

75. The spindle of Figs. 1 and 2 is provided with

cap members 50 on the ends, the outer faces of said cap members being provided with circular concavities 51 each having a diametrically arranged slot 52a therein. These end members facilitate mounting of the spindle in a machine and are adapted to cooperate with the supporting and driving parts of a machine shown in Fig. 1. As here shown, 52 and 53 indicate bearing or socket members for rotatably supporting the cap members 50. 54 indicates a spring-pressed plunger seated in the concavity 51. In Fig. 1, 55 indicates a driving member provided on its end with a blade 55 adapted to enter the slot 52a for the purpose of rotating the spindle.

In the spindle of Figs. 6, 7, 8, 9 and 10 the same is provided with cap members 150 on the ends, each of said cap members carrying a pintle 151 having a flattened portion 152. The cap member 150 is provided with a slot in which the inner end of the member 152 is inserted, the attachment being effected by clamping, welding, soldering or other suitable means. Certain portions of a machine for supporting this spindle are shown in Fig. 6. As here shown, one side of the machine carries a bearing block 157 adapted to receive the pintle 151 and permit free rotation of the latter therein. 158 indicates a driving member for the spindle and this is provided with a socket to receive the pintle 151. This member 158 is extended and provided with parallel jaws 30 160 to engage the flattened member 152 to effect rotation of the spindle.

While we have shown and described certain embodiments of our invention, it is to be understood that it is capable of many modifications. 35 Changes, therefore, in the construction and arrangement may be made without departing from the spirit and scope of the invention as disclosed in the appended claims, in which it is our intention to claim all novelty inherent in our invention as broadly as permissible, in view of the prior art.

What we regard as new, and desire to secure by Letters Patent, is:

1. In a duplicating machine, a spindle having a flattened face with a slot therein, a gelatin band and a fastening clip formed of a single piece of sheet metal and attached to one end of said band, said clip having a portion adapted to lie on said flattened face and provided with a tongue 50 to enter said slot, the outer edge of the tongue being joined by a portion of metal to one edge of the portion of the clip adapted to lie on the flattened face of the spindle, the end of the band being clamped between said portions of said 55 clip.

2. In a duplicating machine, a spindle having a flattened face with a slot therein, a gelatin band and a fastening clip attached to one end of said band, said clip having a portion adapted 60 to lie on said flattened face and provided with a tongue adapted to enter said slot, said tongue being formed of two layers of material with the end of the band clamped therebetween.

3. The combination with a spindle having a flattened face with a slot therein, of a flexible band, and a fastening clip attached to one end of said band, and adapted to lie on said flattened face within the boundaries thereof, said clip having a tongue adapted to enter said slot. 65

4. The combination with a spindle having a flattened face with a slot therein, of a flexible band, and a fastening clip attached to one end of said band and adapted to lie on said flattened face within the boundaries thereof, said clip 70 75.

having a tongue adapted to enter said slot and said tongue being clamped to said end of said band.

5. The combination with a spindle having a flattened face with a slot therein, of a flexible band, and a fastening clip attached to one end of said band and adapted to lie on said flattened

face within the boundaries thereof, said clip being formed of a single piece of sheet metal clamped to said end of said band and formed into a tongue adapted to enter said slot.
